UNITED STATES PATENT OFFICE

LOUIS V. ARONSON AND FREDERICK MEYER, OF NEWARK, NEW JERSEY; SAID MEYER
ASSIGNOR OF HIS ENTIRE RIGHT TO SAID ARONSON

SOUNDING DEVICE

Application filed January 31, 1925. Serial No. 5,949.

Our invention relates to improvements in sounding devices and more particularly to sounding devices adapted to be placed in dolls or toys to cause them to automatically speak when moved to different positions. The main object of the invention is to provide a device of this class which is not only simple and efficient in operation but which can be easily and cheaply assembled and the parts of which may be easily and cheaply made.

Further and more specific objects, features and advantages will more clearly appear from the detail description given below taken in connection with the accompanying sheet 15 of drawings which forms a part of this specification. In the drawings Fig. 1 is a perspective, partly broken away, of a device embodying our improvements in a preferred form thereof. Fig. 2 is a vertical section of 20 the same with the bellows distended. Fig. 3 is a similar section showing the bellows collapsed. Fig. 4 is a plan view of the valve member. Fig. 5 is a plan view of the weighty member with the sound chamber removed. 25 Fig. 6 is a bottom view of the same and Fig. 7 is a plan view of the weighty member with the sound chamber on top thereof.

Referring to the drawings, 1 represents a tubular cylindrical casing preferably made 30 of cardboard or other cheap material, which casing is closed at one end by sheet metal cap member 2. 3 represents a tubular bellows member, the lower end of which is closed by the cap member 2 and is secured about the 35 edges of the casing 1 thereat by the peripheral flange 4 on the cap member 2. 5 represents a weighty member of iron or other metal, circular in shape and provided with a peripheral depending flange 6. The upper end of the 40 tubular bellows 3 is secured about the periphery of the member 5 by a depending peripheral flange 7 on a member 8, the member 8 being dished so that the main body portion thereof is spaced from the body portion of 45 the member 5 so as to provide a sound chamber 10 between the two. 9 represents a sounding element comprising a reed pipe with a reed which extends into an opening through the weighty member 5 whereby upon the 50 bellows being compressed and air forced out

thereof, the air will be forced through the reed pipe causing the reed to speak and the sound therefrom to issue into the sound chamber 10. The top of the sound chamber is provided with four openings 11 through 55 which the sound from the sound chamber may be emitted. Crimped on to the other end of the casing 1 is a perforated sheet metal cap member 12 and extending between the caps 2 and 12 is a metal rod 13. The rod 13 is held fixed with respect to the casing by means of 60 depressions 14 and 15 stamped up in the cap members 2 and 12 respectively and into which depressions the ends of the rod 13 are fitted. The rod 13 is square in cross section and the 65 depressions 14 and 15 may be made square in cross section so as to prevent the rod from turning or the rod may be clamped between the cap members with sufficient pressure to prevent the rod from turning easily. The 70 rod 13 passes through the bellows and through a square opening 20 in a central depressed portion of the weighty member 5 and through the sound chamber and through a circular opening 21 in the member 8. The rod 13 is 75 thus made non-rotatable with respect to the weighty head and sound chamber. 16 represents an oscillating valve member adapted to 80 rest by gravity on the top of the sound chamber member 8. The valve member 16 is provided with four openings 17 adapted to register with the openings 11 and it is stamped up at the center thereof and provided with a central opening 18 through which the rod 13 passes. This opening 18 is made square in 85 cross section. The rod 13 is twisted a quarter of a turn at 19 so as to provide spiral cam 90 faces thereon and since the rod is non-circular in cross section and twisted and the opening in the valve member 16 conforms to the cross section of the rod, then when the valve member slides down along the rod 13, it will 95 be caused to rotate about the axis of the rod 13 causing the openings 17 to slide over the top of the sound chamber and hence over the openings 11 therein.

In operation the device is first turned so 100

that the weighty member 5, with the sound chamber and the valve 16, slides by gravity along the rod 13 so as to distend the bellows as shown in Fig. 2. Then the position of the 5 device is changed to the upright position shown in Fig. 2 or so that the weighty member 5 with the sound chamber and valve 16 will slide down along the rod 13 to the position shown in Fig. 3. During this movement 10 the bellows will be compressed and the air therein forced out through the reed pipe 9 causing the same to speak and the sound therefrom to be emitted into the sound chamber. During this movement there will be no 15 rotation of the weighty member and sound chamber with respect to the rod 13 because the square hole 20 is made to conform to the cross section of the rod, and this hole 20 being always below the twisted portion 13 there 20 will be no rotation of the weighty member or sound chamber or rod with respect to one another. At the start of the compression movement the openings 17 register with the openings 11 so that the sound from the reed 25 pipe is emitted from the sound chamber through these openings and out of the device through the perforated cap 12. As the movement collapsing the bellows progresses the valve member 16 is caused to oscillate by reason of the twisted portion 19 so that the openings 17 no longer register with the openings 11 thereby interrupting the emission of 30 sound from the sounding element. There is sufficient leakage of air from the bellows, 35 however, to permit the continual collapsing thereof and as the parts move further along the rod 13, the rotary movement of the valve member 16 will be continued until the openings 17 again register with the openings 11 thereby permitting the sound from the reed 40 pipe to again issue from the sound chamber. In this way, during the collapsing of the bellows, the device is caused to issue a sound like "Ma-Ma" or the like. The bellows may 45 again be distended for another operation by simply changing the position of the doll or toy so that the weighty parts 5 and 16 will slide back to distend the bellows as shown in Fig. 2. It will be understood that the opening 50 in the member 8 through which the rod 13 passes is circular in cross section so that the twists in the rod 13 do not cause this member to rotate with respect to the casing. The valve member 16 is free to slide on the rod 13 55 independently of the weighty member 5 and sound chamber member 8 and merely rests on the top of the member 8 by gravity. If the valve member 16 should become separated 60 from the member 8, it will immediately fall back and rest by gravity on the member 8 as soon as the device is put into a position tending to collapse the bellows by the weight of the members 5 and 8.

65 It will thus be seen that we have provided

an arrangement for the purpose described, the parts of which are not only simple and easily manufactured, but which are also easily and conveniently assembled and which is efficient and certain in operation.

While we have described our improvements in great detail and with respect to a preferred form thereof, we do not desire to be limited to such details or forms since many changes or modifications may be made and the invention embodied in widely different forms without departing from the spirit and scope of our invention in its broader aspects. Hence we desire to cover all modifications and forms coming within the language or scope of any one or more of the appended claims.

What we claim as new and desire to secure by Letters Patent, is:

1. A sounding device having in combination a casing, a weighty member adapted to slide back and forth in the casing by gravity, a sound chamber carried with the weighty member, means including a sounding element whereby upon movement of said member in the casing the sounding element is caused to sound by means of air forced therethrough, said sound chamber being provided with an opening through which the sound is adapted to issue, an oscillating valve member provided with a part adapted to slide over said sound chamber opening to control the emission of sound therefrom, and means whereby movement of said weighty member in the casing causes said valve member to rotate with respect to the sound chamber.

2. A sounding device having in combination a collapsible air chamber, a sound reed operated thereby, means having an opening through which the sound from the reed may issue, a valve adapted to rotate over said opening to control the issuance of sound therefrom, and a member having a spiral cam face acting to rotate said valve over said opening, said valve sliding with respect to said member whereby the member causes rotation of the valve when the collapsible air chamber is operated.

3. A sounding device having in combination a bellows with two heads, one of said heads being a weighty head whereby it may operate the bellows by gravity, a sound reed operated by the bellows, means having an opening through which the sound from the reed is adapted to issue, a valve having a plurality of apertures therethrough adapted to rotate over said opening to control the issuance of sound therefrom, and a member having a cam face, said valve being slidable with respect to said member, the cam member acting on the valve to rotate the same as the bellows is operated.

4. A sounding device having in combination a casing, a weighty member adapted to slide back and forth in the casing by grav-

ity, a sound chamber carried with the weighty member, means including a sounding element whereby upon movement of said member in the casing the sounding element 5 is caused to sound by means of air forced therethrough said sound chamber being provided with an opening through which the sound is adapted to issue, an oscillating valve member provided with a part adapted to slide 10 over said sound chamber opening to control the emission of sound therefrom, and a rod extending in a direction substantially parallel to the movement of the weighty member, and passing through openings in said weighty 15 member and valve, said rod being non-circular in cross-section and twisted and the opening in the valve member conforming to the cross-section of the rod whereby movement of the weighty member and valve member along the rod causes the valve member to rotate with respect to the sound chamber.

5. A sounding device having in combination a collapsible air chamber, a sound reed operated thereby, means having an opening 20 through which the sound from the reed is adapted to issue, a valve adapted to rotate over said opening to control the issuance of sound therefrom, said valve being held adjacent and in operative position to said opening by gravity and a member having a cam face acting to rotate the valve as the collapsible air chamber is operated and said valve being slidable with respect to said cam member.

25 6. A sounding device having in combination a casing, a weighty member adapted to slide back and forth in the casing by gravity, a sound chamber carried with the weighty member, means including a sounding element 30 whereby upon movement of the weighty member in the casing the sounding element is caused to sound and the sound therefrom issues into the sound chamber, said sound chamber being provided with an opening therethrough, a rod extending through said weighty member and a valve member adapted to rotate about the axis of said rod and having a part adapted to oscillate over said sound chamber opening to control the emission of sound therefrom, said valve member 35 being freely movable along said rod independently of said weighty member and sound chamber and adapted to rest on the sound chamber by gravity.

40 7. A sounding device having in combination a casing, a weighty member adapted to slide back and forth in the casing by gravity, a sound chamber carried with the weighty member, means including a sounding element 45 whereby upon movement of the weighty member in the casing the sounding element is caused to sound and the sound therefrom issues into the sound chamber, said sound chamber being provided with an opening therethrough, a rod extending through said

50 weighty member and a valve member adapted to rotate about the axis of said rod and having a part adapted to oscillate over said sound chamber opening to control the emission of sound therefrom, said valve member being freely movable along said rod independently of said weighty member and sound chamber and adapted to rest on the sound chamber by gravity, said rod passing through openings in said weighty member and valve member and being non-circular in cross-section and twisted and the opening in the valve member conforming to the cross section of the rod whereby movement of the weighty member and valve member along the rod causes the valve member to rotate with respect to the sound chamber.

55 8. A sounding device having in combination a tubular casing, a tubular bellows, one end of which is secured to the closed end of the casing, a weighty member closing the other end of the bellows and adapted to move back and forth in the casing by gravity, a rod, extending through the bellows and weighty member at right angles to the movement of the latter and fixed with respect to the casing, a member having its periphery clamped about the periphery of the weighty member and securing the end of the bellows thereto and forming a sound chamber on the 60 weighty member, a sounding element carried by the weighty member and adapted to sound and emit sounds into the sound chamber upon compression of the bellows by the weighty member, said sound chamber having an opening for the emission of sound therefrom and a perforated valve disc adapted to rest by gravity on the sound chamber and having an opening through which said rod passes, said rod being non-circular in cross-section and twisted and the opening in the valve member conforming to the cross section of the rod whereby movement of the weighty member and valve member along the rod causes the valve member to rotate with respect to the sound chamber.

65 9. A sounding device having in combination a bellows with two heads, one of said heads being a weighty head whereby it may operate the bellows by gravity, a sound reed operated by the bellows, a sound chamber carried by the weighty head, and into which chamber the sound from the reed issues, said sound chamber having an opening through which the sound is adapted to issue, a valve 70 having a plurality of apertures therethrough adapted to rotate over said opening in a plane parallel with the face of the opening to control the issuance of sound therefrom, and a means having a cam face acting to rotate the valve over said opening as the bellows is operated.

75 10. A sounding device having in combination, a bellows with two heads, one of said heads being a weighty head whereby it may 80

operate the bellows by gravity, a sound reed operated by the bellows, a sound chamber carried by one of the heads, and into which chamber the sound from the reed issues, said sound chamber having an opening through which the sound is adapted to issue, a valve adapted to rotate over said opening to control the issuance of sound therefrom, and a member having a spiral cam face extending through said valve and acting to rotate the valve as the bellows is operated, said valve being slidable on said member.

10 11. A sounding device having in combination a bellows with two heads, one of said heads being a weighty head whereby it may operate the bellows by gravity, a sound reed operated by the bellows, a sound chamber carried by one of the heads, and into which chamber the sound from the reed issues, said sound chamber having an opening through which the sound is adapted to issue, a valve adapted to rotate over said opening to control the issuance of sound therefrom, and a member having a spiral cam face acting to 20 rotate the valve as the bellows is operated, said valve being slidable with respect to said cam member and held by gravity adjacent and in operative position flat against the 25 said opening.

30 12. A sounding device having in combination a bellows with two heads, one of said heads being a weighty head whereby it may operate the bellows by gravity, a sound reed operated by the bellows, a sound chamber 35 carried by one of the heads, and into which chamber the sound from the reed issues, said sound chamber having an opening through which the sound is adapted to issue, a valve adapted to rotate over said opening to control the issuance of sound therefrom, and a member having a spiral cam face extending through said weighty member, sound chamber and valve, and acting to rotate the valve as the bellows is operated, said member being non-rotatable with respect to the sound 45 chamber.

In testimony whereof we have signed our names to this specification.

LOUIS V. ARONSON.
FREDERICK MEYER.
